CLAIM

The ornamental design for window removal prevention device, substantially as shown and described.

DESCRIPTION

FIG. 1 is a perspective view of a window removal prevention device showing my new design in the top channel of the window, it being understood that the broken line showing of the window is for illustrative purposes only;

FIG. 2 is a front elevational view;

FIG. 3 is a side elevational view;

FIG. 4 is a top plan view; and

FIG. 5 is a bottom plan view.
